BARBECUE GRILL

Jefferson Roy Lowry, Fort Worth, Tex., assignor to Jeff Lowry Iron Works, Inc., Fort Worth, Tex., a corporation of Texas

Application March 16, 1955, Serial No. 35,059

Term of patent 3½ years

(Cl. D81—10)

Figure 1 is a front perspective view of a barbecue grill embodying my new design with the cover in closed position and the grid omitted for convenience of illustration; and

The undisclosed portions of the cover are substantially plain.

I claim:

The ornamental design for a barbecue grill, substantially as shown and described.
